UNITED STATES PATENT OFFICE.

WILLIAM MILTON BROWN, OF JOHNSTOWN, PENNSYLVANIA.

SWITCH STAND.

1,416,397.

Specification of Letters Patent. Patented May 16, 1922.

Application filed September 29, 1921. Serial No. 504,183.

To all whom it may concern:

Be it known that I, WILLIAM MILTON BROWN, a citizen of the United States, and resident of Johnstown, in the county of Cambria and State of Pennsylvania, have invented certain new and useful Improvements in Switch Stands, of which the following is a specification.

This invention relates to switch stands, 10 and more particularly to switch stands having means for preventing the falsifying of the target when the switch is trailed.

The invention consists broadly in providing a resilient connection between the operating lever and operating shaft, that will 15 normally remain in operative position, but will be forced into inoperative position and allow free movement of the operating shaft, target shaft, etc., when the switch is trailed, 20 thus preventing the breaking of any parts or the falsifying of the target.

One object of this invention is to provide a connection of the character described, that 25 may be readily reset after the switch has been trailed, without the substitution or dismantling of any of the parts of the stand.

A further object of the invention is to provide a connection of this character that 30 will be efficient in operation, strong and durable, and inexpensive to manufacture.

The above and various other objects and 35 advantages will be brought out in the following specification and illustrated in the accompanying drawings, in which—

Figure 1 is a side elevation of a switch stand embodying my invention.

Figure 2 is a top plan thereof.

Figure 3 is an enlarged detail elevation 40 of a portion of the operating lever showing its connection with the operating shaft.

Figure 4 is a plan of the detail shown in Figure 3.

Figure 5 is a detail elevation showing the 45 position of the connecting pin when the switch is trailed.

Referring particularly to the drawings, 2 50 designates the usual switch stand casing, in which is journaled the target shaft 3, having a target 4 on its upper end. The target shaft 3 has a bevel gear 5 secured thereon intermediate its ends which is in mesh with a bevel gear 6 secured on one end of an operating shaft 7 which extends at right angles to the shaft 3 and is journaled in suitable 55 bearings in the casing 2. A counterweighted hand operating lever 8 is mounted adjacent

the free end of the shaft 7, which projects through the casing 2, and is free to rotate thereon.

The lower end of the target shaft 3 is provided with an offset head 9 having a screw threaded aperture therein for the reception of a screw threaded crank arm 10 which has a pivotal connection with one end of the switch rod link 11. The other end of the 60 link 11 is connected to the usual switch rod. 65

The free end of the shaft 7 beyond the lever 8 is squared and a collar 12 is fitted thereon and secured in place by a pin 13.

An outwardly flared recess or notch 14 is 70 formed in the periphery of the collar 12 and is adapted to receive the tapered head 15 of the locking pin 16. The pin 16 is slidably mounted in apertured lugs 17 on the lever 8 and is provided intermediate its ends 75 and between the lugs 17 with shouldered spring retaining disks 18. A coil spring 19 is mounted around the pin 16 between the disks 18 and the lower disk, that is, the disk nearest the head 15 of the pin is adjustably 80 locked in position on the shank of the pin by nuts 20. It will thus be apparent that the tension of the spring 19 is conveyed through the lower disk to the pin 16, and this tension may readily be varied by adjusting the nuts 20 to vary the position of the lower disk. 85

It will be apparent from the above that the pin 16 and collar 12 form a resilient connection between the lever 8 and shaft 7. 90

The usual locking mechanism 21 is provided at each side of the switch stand casing for locking the lever 8 in its terminating positions.

The spring 19 is of such strength as to 95 normally hold the head of the pin 16 in the recess 14. However, if the switch be accidentally trailed by a locomotive or cars while the operating lever is locked in position, the pin 16 will be forced out of the recess 14 and the switch stand parts will be 100 free to operate without being damaged, and the target will be turned to indicate the true position of the switch. If a switch should thus be trailed, no parts of the stand are 105 damaged, the target is not falsified, and it is only necessary to rotate the lever 8 about shaft 7 until the head 15 of pin 16 again aligns with the recess 14 when the spring 19 will force it into place and the stand is again 110 in normal condition.

While I have illustrated only one, pre-

ferred, form of my invention, I do not wish to be limited thereto, since various modifications in design and combination of parts may readily be made by those skilled in the art without departing from the spirit of my invention as defined in the appended claims.

I claim—

1. In a switch stand having a vertical target shaft, an operating shaft operatively connected to said target shaft, and an operating lever mounted to freely rotate on said operating shaft, means for connecting said operating shaft and said lever, said means being adapted to remain in operative position during the normal operation of said stand and to automatically release said shaft when the switch is trialed.

2. In a switch stand having a vertical target shaft, an operating shaft operatively connected to said target shaft, and an operating lever mounted to freely rotate on said operating shaft, a collar secured to said operating shaft, and resilient means connecting said lever and said collar, said means being adapted to remain in operative position during the normal operation of said stand and to automatically release said shaft when the switch is trialed.

3. In a switch stand having a vertical target shaft, an operating shaft operatively connected to said target shaft, and an operating lever mounted to freely rotate on said operating shaft, a collar secured to said operating shaft, and a spring pressed pin mounted on said lever and engaged in a socket in said collar adapted to form an operative connection between said lever and said operating shaft, said pin being adapted to remain engaged in said socket during the

normal operation of said stand and to be automatically disengaged from said socket if the switch is accidentally trialed.

4. In a switch stand having a vertical target shaft, an operating shaft operatively connected to said target shaft, and an operating lever mounted to freely rotate on said operating shaft, a collar having an outwardly flaring recess in its periphery secured on said operating shaft, and a spring pressed pin mounted on said lever and provided with a tapered head adapted to be engaged in said recess in said collar to form an operative connection between said lever and said operating shaft, said pin being adapted to remain engaged in said socket during the normal operation of said stand and to be automatically disengaged from said recess when the switch is trialed.

5. A switch stand having a vertical target shaft, an operating lever mounted to freely rotate on said operating shaft, and a crank arm secured to the lower end of said target shaft and adapted to be connected to the switch rod, a collar having an outwardly flaring recess in its periphery secured on said operating shaft, and a spring pressed pin mounted on said lever and provided with a tapered head adapted to be engaged in said recess in said collar to form an operative connection between said lever and said operating shaft said pin being adapted to remain engaged in said socket during the normal operation of said stand and to be automatically disengaged from said recess when the switch is trialed.

In testimony whereof I have hereunto set my hand.

WILLIAM MILTON BROWN.
